(57) **CLAIM**

The ornamental design for a paper food container, as shown and described.

DESCRIPTION

FIG. 1 is a perspective view of a paper food container showing my new design, according to a first embodiment; FIG. 2 is a top plan view thereof;

FIG. 3 is a bottom plan view thereof;

FIG. 4 is a right side view thereof, the left side, front elevational and rear elevational views being identical thereto;

FIG. 5 is an enlarged cross-sectional view taken along line 5-5 of FIG. 1;

FIG. 6 is an enlarged cross-sectional view taken along line 6-6 of FIG. 1;

FIG. 7 is a perspective view of a paper food container showing my new design, according to a second embodiment;

FIG. 8 is a top plan view thereof;

FIG. 9 is a bottom plan view thereof;

FIG. 10 is a front elevational view thereof, the rear elevational view being identical thereto;

FIG. 11 is a right side view thereof, the left side view being identical thereto;

FIG. 12 is an enlarged cross-sectional view taken along line 12-12 of FIG. 7; and,

FIG. 13 is an enlarged cross-sectional view taken along line 13-13 of FIG. 7.

The broken lines shown in FIGS. 3 and 9 depict portions of the paper food container that form no part of the claimed design.
